2,517,704

FILTER FABRIC STRUCTURE AND PROCESS
OF MAKING SAME

John Overbeke, Cleveland Heights, Ohio

Application October 13, 1945, Serial No. 622,197

13 Claims. (Cl. 210—169)

1

My invention relates to fabric structures and more particularly to fabric structures wherein a fabric conduit or tube is joined to a fabric wall member in communication with an opening in the wall member, such as in a filter or similar structure, and is related to the process of making such a fabric structure.

An object of my invention is to provide an improved fabric structure having improved strength and durability.

Another object is to provide an efficient joint or connection between a fabric conduit or tube and a flat wall member.

Another object is the provision for the improved securement of the end of a conduit or tube composed of fabric or textile to a flat member or sheet also composed of fabric or textile.

Another object is the provision of an improved conduit connecting two fabric wall members.

Another object is the provision of an improved fabric structure for a filter or like structure.

Another object is the provision of an improved process for making the described structure.

Another object is the provision of an improved method of assembling and securing together a fabric conduit or tube to a wall member.

Another object is the provision of an improved process for mounting a fabric conduit or tube between spaced wall members of fabric to place openings in the wall members in communication.

Other objects and a fuller understanding of my invention may be had by referring to the attached drawings in which:

Figure 1 is a side view of my improved fabric structure looking into the side of the conduit or tubular member, and showing portions of the side walls cut away at the ends thereof as unnecessary for the illustration of my invention;

Figure 2 is a longitudinal sectional view through Figure 3 in the direction of the arrows 2—2;

Figure 3 is an end view of the structure shown in Figure 1 looking in the direction of the arrows 3—3, and is a view of a portion of a wall member with unnecessary parts cut away and is a view looking through the open conduit or tube;

Figure 4 is a view of a modified form of my structure as shown in Figures 1, 2, and 3 and illustrates two conduits or tubes of different sizes arranged in series;

Figure 5 illustrates a flat piece of fabric or textile out of which the conduit or tube of my structure may be formed, the piece of fabric or textile being woven on a bias to the edges of the piece;

Figures 5 to 10, inclusive, illustrate steps of a process which may be utilized to advantage in making my improved structure, the views of these steps being illustrative rather than limiting in nature;

Figure 6 illustrates the step of forming a conduit or tube out of the material shown in Figure 5 by rolling and sewing the same as shown;

2

Figure 7 is a view illustrating a further step in my method of making the improved structure;

Figure 8 illustrates a subsequent step in my improved method;

Figure 9 illustrates another subsequent step in my improved method; and

Figure 10 illustrates another subsequent step in the carrying out of my improved method.

Referring to the views of Figures 1, 2, and 3, there is shown a fabric conduit or tube 11. At opposite ends of the tube 11 there are two spaced fabric wall members or flat sheets 16. In the use of my fabric construction in a filtering apparatus, the conduit 11 and walls 16 are made of a fabric appropriate for the filtering to be performed, and by way of example may be canvas, twill, felt or other textile and may be a treated fabric or not, according to the filtering requirements. The two wall members 16 have holes or openings therein of similar size and arranged in alignment with each other. The tube 11 joins the two wall members around the circumference of these holes or openings to place the holes or openings in direct communication. As the size and outer extremes 25 of the wall members 16 are immaterial to the nature of the invention, the wall members 16 are shown cut away at a distance from the tube 11. The warp and weft in the fabric of tube 11 is on a bias to the longitudinal axis of tube 11. Similarly, the warp and weft of the fabric is on a bias to the edge of the fabric at the ends of the tube 11 joining the wall members 16.

In my invention, the opposite end portions of tube 11 are flared radially outward to form the flanges 12 on the ends of tube 11 and the flanges 12 extend continuously around the tube 11 without "snips" or "pie-cuts" therein. It is possible to have the flanges 12 extend out at right angles to the body of the tube 11 in this manner only because of the bias-cut at the ends of the tube 11. By having the warp and weft of the fabric at the ends of the tube disposed on a bias the fabric may be stretched and flared at the ends to form the flanges 12 without cutting it and without rupture. Were the ends of the tube 11 not cut on a bias as described it would not be possible or practical to form the flanges 12 extending uninterruptedly around the circumference of the tube. The continuous and uninterrupted nature 50 of the flanges 12 is such that there are no holes, cracks, or leaks through the flanges 12 as would be present where "snips" or "pie-cuts" are used.

A fabric or cloth washer 13 of annular shape is mounted around each end of tube 11 and adjacent the flange 12. The washers 13 overlap the edges of the flanges 12 and engage the wall members 16 in the region beyond the circumference of the flanges 12. The inner diameter of the washers 13 is approximately the same as the outer diameter of the tube 11. The outer diameter of the washers 13 is somewhat more than the outer di-

diameter of the flanges 12 so as to overlap the edge of the flanges 12. The washers 13 are flat pieces of fabric conformed to the other parts with which they are in engagement.

A thin layer of glue or other suitable adhesive 22 is positioned between the washers 13 and flanges 12 to provide adherence between the two. Another thin layer of glue or other suitable adhesive 23 is positioned between the flanges 12 and the wall members 16. The layers of glue or other adhesives 22 and 23 extend continuously around the circumferential extent of the flanges 12.

Threaded stitching or sewing 15 extends through the washers 13, flanges 12, and wall members 16, respectively, completely around the circumferential extent of the flanges 12. The stitching 15 is sufficiently close and tight as to firmly and securely bind the parts together without cracks or leakage therebetween.

An annular row of stitching or sewing 14 tightly secures the washers 13 to the wall members 16 at the outer peripheral edges of the washers 13. The stitching 14 extends around the circumferential extent on the outer edge of the washers 13.

The annular row of stitching 15 is referred to as the inner stitching and the annular row of stitching 14 is referred to as the outer stitching. Stitching 14 and 15 is of the zig-zag variety and preferable form, as shown in Figure 3, and tightly binds the parts together in firm securing and without openings or gaps.

As the layers 22 and 23 of glue or other adhesive are for the primary purpose of maintaining the parts in position during the sewing of the stitch rows 14 and 15, it may be that in filtering some materials the glue or other adhesive 22 and 23 may dissolve or otherwise disappear in time. It is therefore to be understood that the glue or adhesive layers 22 and 23 may not always be present. In most instances the stitching 14 and 15 may be depended upon to provide a tight and secure engagement between the parts throughout use of the structure. The layers of glue or other adhesive 22 and 23 may persist and be present and for filtering some materials it may be preferable to use a non-disolving glue or other adhesive which will remain present and afford additional sealing effects.

It will be readily understood for purposes of clarity in illustration that the thickness of the parts has been exaggerated and the spacing is not necessarily proportional.

As shown and described, there is thus provided an improved fabric structure and particularly an improved connection or joint provided between the tube 11 and the wall members 16. Leakage and wear is considerably reduced and an efficient and durable fabric structure, such as when utilized in a filter, is provided. The improved fabric structure is advantageous in many respects and its utility for all uses where appropriate will be readily understood.

In Figure 4, there is a modified form of structure embodying principles of my invention. In Figure 4, the right-hand wall member, denoted by the reference character 17, extends inwardly and has a smaller opening than the left hand wall member 16. The tube or conduit 18 of reduced diameter is joined to the wall member 17 in communication with the small opening therein in the same manner as described for the tube 11 and wall member 16 in connection with Figures 1, 2, and 3. As thus shown in Figure 4, a series of tubes varying in diameter may be

mounted in a series by means of my improved connecting means. The tube 18 is similar to tube 11 as also being cut on a bias and having a flange formed on its end by flaring the bias-cut end.

In Figures 5 to 10, inclusive, there is illustrated a series of steps which may be followed in my improved method of joining a fabric tube to a fabric wall member. As shown in Figure 5, a flat piece of suitable fabric or textile material may be used to form the tube 11. The piece of fabric is cut diagonally to the warp and weft of the fabric so that the top edge 19 and bottom edge 20 may be said to be cut on a bias. The piece of material shown in Figure 5 is then rolled into a tube or cylinder as shown in Figure 6, the edges 19 and 20 forming the ends of the tube. The tube 11 is held in a formed and closed position by the longitudinal stitching or sewing 21, also of the zig-zag type. It is to be understood that the tube 11 does not necessarily have to be made of flat pieces of fabric but may be made of a long fabric hose or tubing. Such a long hose or tubing as is suitable for my invention is woven on a bias, that is, the warp and weft of the fabric in the long hose or tubing is disposed on a bias to the longitudinal axis of the hose or tubing. When the tube 11 is made from long hose or tubing rather than formed from a flat piece of material, the long hose or tubing woven on a bias is cut up into suitable lengths to form the tube 11. In such a case, the stitching 21 as shown in Figure 6, would not be present.

In Figure 7, the next step in my improved process is shown. The bias-cut ends of the tube 11 are flared radially outward of tube 11 to form flanges 12 on opposite ends of the tube. It is possible to form a flange 12 without "snips" or "pie-cuts" because the disposition of the warp and weft of the fabric being on a bias permits the end edges to be stretched and extended outwardly without tearing. Having flanges 12 extend continuously around by such stretching and flaring not only reduces the labor involved but also assures that there are no leaks or gaps in the flanges around the tube. If there were such gaps as would be occasioned by "snips" or "pie-cuts," there would be grave danger that the stitching 15 would miss closing such gaps completely and a leaky opening would be possible. By my method of forming the flanges, a tight sealed connection is made possible.

A subsequent step of my method is illustrated in Figure 8. Here a thin coating of glue or other adhesive 22 is placed on one side of the flange 12 and the fabric washer 13 is placed down over the flange 12 around the tube 11 in contact with the said adhesive layer 22. The adhesive 22 firmly binds the flange 12 to the inner peripheral portion of the washer 13.

A subsequent step is shown in Figure 9 wherein the tube 11 and washer 13 are placed adjacent a wall member 16 with the tube 11 in register with the opening in the wall member 16. Another layer 23 of glue or other adhesive is applied between the flange 12 and wall member 16. Thus the washer 13, the flange 12, and the wall member 16 are held in firm and fixed position by the layers 22 and 23 of glue or other suitable adhesive. The principle function of the glue or other adhesive is to firmly hold the parts in a fixed position while putting the parts through the sewing operation. Without being thus held adhesively during the sewing operation, the tube 11 will kink and twist relative to the wall mem-

ber 16. Such kinking and twisting of tube 11 makes it extremely difficult and almost impossible to properly sew together the washer 13, flange 12, and wall member 16. However, by having the adhesive hold the parts securely during the sewing operation there is no wrinkling of the fabric, no kinking or twisting, and no unevenness in the sewing.

The subsequent step of sewing or stitching the parts together is shown in Figure 10. The inner 10 annular row of stitching 15 extends through the washer 13, flange 12, and the wall member 16 immediately next to the opening in the wall member 16. The outer annular ring of stitching 14 secures the washer 13 in overlapped position over the edge of the flange 12 to the wall member 16. As shown in Figure 3, the stitching 14 and 15 is preferably of the zig-zag type with the stitches close together and tightly holding the fabric parts together. By the arrangement shown, rough edges are eliminated and there is a free uninterrupted flow provided between the opening in wall member 16 and the tube 11. The adhesive in the layers 22 and 23 may be dissolvable for some uses and disappear. In other uses, the adhesive may not dissolve and may be retained in position to further seal the parts together. In those uses wherein the adhesive may dissolve and is not necessary in use for sealing purposes, the stitching seam of a tight close kind holds the overlapped fabric parts together in a tight connection. The layers 22 and 23 being very thin do not loosen the hold of the stitches upon dissolving. As stated, the primary function of the layers 22 and 23 of adhesive is to hold the parts in firm engagement during assembly and particularly during the stitching operation.

In the utilization of my improved fabric structure in a filtering apparatus, the peripheral edges of sheets 16 are secured to opposite walls of an enclosed chamber of a filtering apparatus so as to divide the chamber into compartments separated by sheets 16. It is understood that there may be any desired number of conduits 11 connecting the sheets 16. Since the sheets 16 are spaced from each other there is an intermediate compartment provided between sheets 16 as well as spaced compartments on the outer sides of sheets 16. The conduits 11 provide open communication between the spaced compartments provided on the outer sides of sheets 16. The fluid containing material to be filtered out, as for example, water containing dirt, may be introduced into the intermediate compartment. The water or other fluid will seep through the fabric of the sheets 16 and conduit 11 into the spaced compartments and the dirt or other filterable material retained in the intermediate compartment. Or the operation may be reversed by introducing the fluid containing filterable material into the opposite spaced compartments and the fluid after filtering through the fabric enters the intermediate compartment. Suitable supporting or bracing members may be utilized for aiding in holding the sheets apart in parallel relationship.

There is thus shown an improved fabric structure and an improved method of making it which is important and useful in many respects, such as for utilization in filters and other devices, wherein in a tube or conduit is connected to a wall member and particularly to a wall member having an opening registering with the tube or conduit.

Although I have described my invention in its preferred form with a certain degree of particularity, it is understood that the present disclosure

of the preferred form has been made only by way of example and that numerous changes in the details of construction and the combination and arrangement of parts may be resorted to without departing from the spirit and the scope of the invention as hereinafter claimed.

What is claimed is:

1. A fabric structure comprising, in combination, a pair of flat fabric members spaced from each other and substantially parallel to each other, said fabric members having openings therein substantially in alignment, a tubular fabric member disposed between and connecting said flat members to provide communication between said openings, the warp and weft of said tubular member being disposed on a bias to the longitudinal axis of said tubular member and having end portions flared outwardly to form flanges integral with the tubular member and continuous around the circumferential dimension of the flanges, said flanges being disposed substantially parallel to and adjacent opposing faces of said flat members, a pair of fabric washer members disposed around said tubular member and next adjacent said flanges, respectively, said flanges being disposed intermediate said flat members and said washers, respectively, and threads sewn through said flat members, said flanges and said washers to secure said flat members, said flanges and said washers together to form said structure.

2. A fabric structure comprising, in combination, a tubular fabric member having its threads disposed at an acute angle to a plane disposed at right angles to the longitudinal axis of the tubular member, said tubular member being stretched radially outward at the ends thereof to provide flanges extending continuously around said tubular member and integral therewith, a pair of fabric wall members disposed at an angle to the axis of said tubular member and adjacent said flanges, said wall members having openings registering with said tubular member, a pair of fabric washers disposed adjacent said flanges, respectively, to cover the outer periphery of said flanges, and securing means for securing together said washers, flanges and wall members, respectively, to provide a continuous conduit between said wall members at the said openings.

3. A fabric structure for utilization in a filter, said structure comprising two textile fabric sheets having aligned openings therein and a hollow cylinder of textile fabric joining said sheets at said openings to provide communication between said openings, the said fabric cylinder having its ends cut on a bias to the longitudinal axis of the cylinder and flared out to provide a flange extending uninterruptedly around each of said ends, said flanges being abutted against said sheets around said openings, a textile fabric washer around each end of said cylinder and over-laying the outer peripheral edge of said flanges, and threads securing said flanges, washers and sheets, respectively, together continuously around said cylinder.

4. A fabric structure for utilization in a filter, said structure comprising two textile fabric sheets having aligned openings therein and a hollow cylinder of textile fabric joining said sheets at said openings to provide communication between said openings, the said fabric cylinder having its ends cut on a bias to the longitudinal axis of the cylinder and flared out to provide a flange extending uninterruptedly around each of

said ends, said flanges being abutted against said sheets around said openings, a textile fabric washer around each end of said cylinder and over-laying the outer peripheral edge of said flanges, adhesive material adhering said flanges, washers and sheets, respectively, together, and threads stitched through said flanges, washers and sheets, respectively, around the circumferential extent of said cylinder to join the same together.

5. The process of making a structure having a conduit connecting with a wall member at an end of the conduit, comprising: providing a fabric wall member; providing a piece of fabric; cutting said piece of fabric on a bias at an end thereof; forming said piece of fabric into a conduit with said bias cut at an end thereof; stretching the fabric of said conduit at said end to flare the said end of the conduit; and connecting the flared end of the conduit to said wall member around the conduit.

6. The process of making a structure having a fabric tube connecting with an opening in a wall member, comprising: providing a wall member with an opening therein; forming a fabric tube having an end thereof cut on a bias; flaring said bias-cut end to form a flange extending continuously around said tube; and securing said flange to said wall member around the periphery of said opening.

7. The process of making a structure having a fabric tube connecting with the opening in a fabric wall member, comprising: forming a fabric tube having the warp and weft on a bias to the longitudinal axis of said tube; stretching an end of said tube radially outward to form a flange on said end; applying adhesive and adhering said flange to the wall member around said opening; and sewing said flange to the wall member around said opening.

8. The process of making a structure having a fabric tube connecting with the opening in a fabric wall member, comprising: forming a fabric tube having an end thereof cut on a bias; flaring the bias-cut end to form a flange; providing a fabric washer; placing said flange adjacent said wall member around said opening; placing said washer around said tube and adjacent said flange; applying adhesive to adhere said wall member to said flange and said washer to said flange; and sewing said wall member, flange and washer together around said opening.

9. The process of making a structure having a fabric tube connecting with the opening in a fabric wall member, comprising: forming a fabric tube having the warp and weft thereof disposed on a bias to a plane passing through an end of the tube; flaring said end to form a flange; placing said flange adjacent the wall member around said opening; providing a fabric washer; placing said washer adjacent said flange; adhering said wall member, flange and washer together with adhesive; and sewing said wall member, flange and washer together around said opening and along the inner periphery of said washer and said wall member and washer together along the outer periphery of said washer.

10. The process of forming a structure having a fabric conduit connecting in communication openings in spaced fabric-wall members, comprising: forming a fabric conduit having ends cut on a bias to the planes of the respective wall members; flaring said ends to form flanges on

the ends of the conduit; providing a pair of fabric washers adapted to surround said conduit; assembling said conduit, wall members and washers to position the flanges adjacent the said wall members, respectively, and to position said washers adjacent said flanges, respectively, to overlap said flanges; applying adhesive to adhere said conduit, wall members, and washers together; and sewing the inner edge portion of the washers, the flanges and the wall members, respectively, together, and the outer edge portion of the washers and the wall member, respectively, together.

11. The process of forming a connection between a fabric tubular member and a fabric wall member having an opening therein to provide communication between said tubular member and said opening, comprising: forming said tubular member to provide a bias-cut edge on an end portion thereof; flaring said end portion to form a flange on said tubular member; abutting said flange against said wall member around said opening; applying adhesive between said flange and said wall member; positioning a fabric annular member over said flange and around said tube; applying adhesive between said flange and said annular member; and sewing said wall member, said flange, and said annular member together, while adhered, around the circumference of said opening.

12. The process of making a filter fabric comprising: providing two spaced wall members of fabric material and having aligned openings therein; providing a sheet of fabric having ends cut on a bias; forming said sheet of material into a tube with bias-cut ends; flaring the bias-cut ends to form flanges; providing two fabric washers; placing said washers around said tube; abutting said flanges against the opposing faces of said wall members and around said openings; applying adhesive to hold said flanges and wall members in position; positioning said washers adjacent said flanges and wall members; applying adhesive to hold said washers, flanges and wall members in position; sewing said washers, flanges and wall members together around the periphery of said opening; and sewing said washers and wall members together around the outer periphery of said washers.

13. The process of securing a fabric tubular member to a fabric wall member, comprising: forming a flange on an end of said tubular member, adhering with adhesive said flange to said wall member, and sewing the adhered flange and wall member to secure the same together.

JOHN OVERBEKE.
